(57) **CLAIM**

The ornamental design for a tool trolley, as shown and described.

DESCRIPTION

FIG. 1 is a first perspective view of a tool trolley showing a first embodiment of the new design;

FIG. 2 is a second perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof;

FIG. 8 is a bottom view thereof;

FIG. 9 is a first perspective view of a tool trolley showing a second embodiment of the new design;

FIG. 10 is a second perspective view thereof;

FIG. 11 is a front view thereof;

FIG. 12 is a rear view thereof;

FIG. 13 is a left side elevational view thereof;

FIG. 14 is a right side elevational view thereof;

FIG. 15 is a top view thereof; and,

FIG. 16 is a bottom view thereof.

The broken lines shown in the figures are for the purpose of illustrating portions of the tool trolley and form no part of the claimed design.
